UNITED STATES PATENT OFFICE.

TREVALYN DAVIS AND LEO E. GARDT, OF CINCINNATI, OHIO.

SWITCH AND SIGNALING DEVICE.

Application filed November 21, 1924. Serial No. 751,382.

Our switching and signaling device is to be used by broadcasting stations and remote control work which is a separate unit of a broadcasting station, when picking up 5 programs away from the station itself.

The object of our invention is to produce a switching and signaling device, which, when made up and wired, can be placed in a compact carrying case, thus making it 10 portable. It is also very simple in construction and operation, and highly efficient in all broadcasting work.

In order to do the signaling or broadcasting we use an extra wire in connection 15 with the regular wiring system between all the implements and parts.

The switching device is so hooked up that we may throw the signal and microphone in the circuit instantly and simultaneously, 20 signaling the speaker, musicians for their particular use, or for others when the particular microphone is ready for one of them, which heretofore has been done by hand signaling, or by personal instructions when 25 to begin, causing a commotion and often-times considerable talk and comment to go out into the air, making it very embarrassing for the particular broadcasting station and the announcer.

30 By using our switch and signal box and giving a few simple instructions before each program, everything will go very smoothly for the announcer or manager in charge, also enabling him by the signal light to tell just what is going on, when any microphone is in the circuit. For example, if it is desired to have the orchestra play at a banquet and it is their time to begin, by throwing the switch the microphone nearest to them will 35 become ready for use and a signal light will be turned on so the orchestra knows they can begin playing. If one of the speakers at the banquet, who is sitting at the speakers' table is ready to speak according to the 40 program, the microphone nearest to the speakers' table will be thrown into operative action and a signal light lit simultaneously so the speaker knows that he is to commence talking, without any instructions, or hand-signaling or other comments.

45 By using this device, it will enable the amplifier operator to put his whole time in modulating the volume, or it can be operated by him very conveniently when connected close to the amplifier.

The various advantages and features of

the invention and details of construction and operation will readily become apparent from reading the specification and claims.

In the accompanying drawing, forming 60 part of this specification:

Fig. 1, is a complete diagrammatic view of the system, including our switching and signaling device,

Fig. 2, is a diagrammatic view of the 65 microphone, and signal light,

Fig. 3, is a diagrammatic view of the output switches,

Fig. 4, is a diagrammatic view of a telephone circuit,

Fig. 5, is a diagrammatic view of the 70 monitoring circuit,

Fig. 6, is an isometric view of our portable carrying and containing case, the working parts of the device or system being carried therein,

Fig. 7, is a similar view with the front 75 door or lid opened, and

Fig. 8, is a similar view with the rear door or cover open.

In the drawing, the switch and signaling device as a unit is marked 1, the transmitters or microphones 2, 2', 2², and 2³, there being four in number in the present instance, and they each carry the signal lights 80 3, 3', 3² and 3³, respectively. The amplifier is marked 4 and the telephone 5.

In order to operate the switch and signal device, we provide a switch case as 1, in which we place an arrangement used for the 85 switch and signal purposes and we will now describe some of the details thereof.

The transmitter or microphone wires are formed in groups of four, A, B, C, and D. These form jacks as shown in Fig. 3, and 90 can be operated by and through the levers or keys 10, 11, 12 or 13, independently or together as the operator desires.

The transmitters 2, 2', 2² and 2³, are operated from the electric contact device or 100 box 1, as follows: If the transmitter 2 is to be used, the lever 10 is thrown into operative connection for connecting the group of wires D in the group of wires E, the current thus passing the amplifier 4 and out through 105 the broadcasting line F.

If the transmitter 2 is not at a convenient point, any of the other transmitters or microphones may be used by operating the proper connections or levers, for example, 110 the microphone 2' is operated by lever or key 11; the microphone 2² being operated

by lever or key 12, and the microphone 2^a by lever or key 13. In operating any of these transmitters or microphones the signal lights 3, 3', 3² or 3³, will light up simultaneously therewith, and show which transmitter or microphone can be used.

These signal lights are wired to and connected with an ordinary 12 volt A battery used in broadcasting, and not shown here, as well known in the art.

The signal light wire is marked 7 and forms one part of the circuit, the lamps or lights being grounded to the base 8, which, in turn, is grounded to the metal shield 9, of the groups of wires A, B, C, and D.

If the operator desires to communicate with the broadcasting station itself, the telephone 5 is used by establishing communications through the wires G. In order to do this the plug key or lever 14 is withdrawn, which closes the circuit, after the phone plugs 15 have been connected to the telephone.

A monitoring circuit is provided by inserting plug or key 16 and this can be done at any time.

In order to eliminate the click in broadcasting, the plug 17 is pulled out, which shorts the circuit.

Our microphone switch and signaling device may be used in connection with any system of wiring other than that herein described, and the switch box for making the same portable may be of any construction desired and found practical. It may be used in connection with any style of microphone and amplifier and in connection with any telephone system or broadcasting system, as it will be just as efficient in its operation in

simultaneously connecting the microphone for operation and the signal light. One or more microphones may be brought into the circuit at the same time.

The signal light wires may be connected up in any desired form found convenient for use.

What we claim as new and our invention and desire to secure by Letters Patent is:

1. In a switch and signal device of the character described, a multiplicity of microphones and a signal light for each, in combination with a switch, means electrically connecting said microphones, said switch and said signals together, said switch capable of being operated to simultaneously place one or more of said microphones in the circuit in condition for use in broadcasting and light one or more of said signal lights, said switch and connections capable of being assembled and made portable.

2. In a switch and signal device of the character described, a multiplicity of microphones and a visual signal for each, in combination with a switch, means electrically connecting said microphones, said switch and the visual signals together, said switch capable of being operated to simultaneously place one or more of said microphones in the circuit in condition for use in broadcasting and to control the actuation of one or more of said visual signals, said switch and connections capable of being assembled and made portable.

In testimony whereof, we affix our signatures at Cincinnati, Ohio, this 19th day of November, 1924.

TREVALYN DAVIS.
LEO E. GARDT.
